UNITED STATES PATENT OFFICE.

CLAUDE L. POST, OF CHICAGO, ILLINOIS.

INKING-ROLLER.

1,398,910.

Specification of Letters Patent. Patented Nov. 29, 1921.

Application filed February 19, 1921. Serial No. 446,363.

To all whom it may concern:

Be it known that I, CLAUDE L. Post, a citizen of the United States, residing at Chicago, in the county of Cook and State of Illinois, have invented certain new and useful Improvements in Inking-Rollers, of which the following is a description.

My invention relates to improvements in inking rollers, and more particularly to an inking roller having an ink-receiving reservoir therein which may be conveniently filled, and being provided with means whereby the ink in said reservoir may be fed to the inking surface at any desired rate of flow.

Another object of my invention is to provide a device of the character described which may be easily assembled and disassembled for inspection or the like, and which is extremely simple, durable, compact, economical, efficient and satisfactory for use wherever found applicable. Many other objects and advantages of the construction herein shown and described will be obvious to those skilled in the art from the disclosure herein given.

To this end my invention consists in the novel construction, arrangement and combination of parts herein shown and described, and more particularly pointed out in the claims.

In the drawings, wherein like reference characters indicate like or corresponding parts,

Figure 1 is an elevation of my device; Fig. 2 is an end view of the same;

Fig. 3 is a section taken substantially on line 3—3 of Fig. 1;

Fig. 4 is a section taken substantially on line 4—4 of Fig. 2;

Fig. 5 is an elevation of a modified form of my device;

Fig. 6 is a section taken substantially on line 6—6 of Fig. 5;

Fig. 7 is a section taken substantially on line 7—7 of Fig. 5;

Fig. 8 is an end view of the device shown in Fig. 5; and

Fig. 9 is a fragmentary section taken substantially on line 9—9 of Fig. 8.

Referring to the drawings, A designates the inking roller in its entirety, said roller comprising a main body section 1, having a convex cylindrical surface which has been cut across on a chord 2. An ink-receiving

reservoir R is provided in said roller and extends substantially the entire length thereof, said reservoir being of any desired shape, preferably as shown in Fig. 3, and having its open side at the chordal surface 2.

Adapted to be detachably secured to the roller 1 is a cover 3, said cover extending across the reservoir, and having its periphery convex and of a degree of curvature equal to that of the inking surface of the roller 1 so as to coöperate therewith to form a substantially cylindrical inking surface for said roller, the inner or flat chordal surface 4 of said cover being preferably tapered toward one of the edges which intersects the segmental surface so that it forms an outwardly divergent aperture with the chordal surface of said roller 1, for a reason to be hereinafter described.

Between the cover 3 and roller 1 is a thin resilient spring plate 5, preferably of metal, said plate extending across the reservoir and being secured along one edge between said cover and plate by screws or the like 6 extending between said cover and roller 1. The forward edge of said plate is preferably adjustably movable between the divergent chordal surfaces of the roller and cover so as to vary the extent of the opening of the passage between the inking periphery and the reservoir R, said adjustment being preferably obtained by providing adjusting screws 7 extending through said cover, as shown in Figs. 2 and 3, and bearing on the plate 5 so that these screws may be manipulated to increase or decrease the width of the opening of the passage, and thereby accordingly regulating the amount of ink flowing therethrough to the inking periphery.

A chamber B extending substantially the length of the roller and either open or closed at its ends is preferably provided adjacent said reservoir so as to maintain a proper balance of the roller, said chamber and reservoir being separated by a longitudinally extending median wall 8. If such a chamber were not provided, the center of gravity would be out of line or to one side of the rotational axis of the roller, and thus the roller would quickly wear in its bearings and also would tend to harm the composition rollers against which it bears.

The ends 9 of the reservoir R are closed, and in either one or both of its end walls are provided closure plugs 10 or with equiva-

lent means, said plugs being removable so that the ink reservoir may be charged with a supply of ink in any suitable manner, as for instance by pressure devices similar to 5 grease guns.

In the modification shown in Figs. 5 to 9, I have provided another form of cover securing means. A plurality of recesses 11, preferably one at each end, as shown in Fig. 10 15, are provided through the web 8 of the roller 1, said recesses being of a size to receive locking bars 12 which are secured to one end of the cover by any suitable means, such as screws 13, the ends 14 of said locking 20 bars being hooked and having arcuate recesses 15 therein adapted to engage the operating bearing lugs 16 and prevent movement therebetween, said lugs being arranged on the roller so as to project into the chamber B and having arcuate ends to engage the arcuate recesses 15 of the locking bars so that when the cover is placed in position the coöperating lugs and bars will hold it in place. The recesses 11 may be enlarged at 25 their outer ends as at 17 so that the locking bars may have a lateral or pivotal movement therein during insertion and removal, and thus permit the assembling and disassembling to be more readily effected.

30 The resilient plate 5 is secured to the cover by screws 18 or any other equivalent means for the purpose, there being an adjusting screw 7, as in the previous modification, bearing on the plate 5, for adjusting the 35 extent of the delivery opening. In order to more securely prevent displacement between the cover and roller, I have provided at the end of the cover opposite to that upon which the locking bars 12 are positioned, a latch 40 19, secured at one or both ends of the cover by screws 20 or other equivalent means for the purpose, the free end of said latch having a pin or offset 21 projecting inwardly therefrom and engageable in a recess 22 provided in the roller.

Having thus described my invention, it is obvious that various immaterial modifications may be made in the same without departing from the spirit of my invention; 50 hence I do not wish to be understood as limiting myself to the exact form, construction, arrangement and combination of parts herein shown and described, or uses mentioned.

55 What I claim as new and desire to secure by Letters Patent is:

1. In a device of the kind described, an inking roller having a reservoir therein opening on the periphery of said roller and 60 adapted to receive a supply of ink, a cover fitting over said reservoir at said peripheral opening, and means for controlling the discharge of ink to the periphery of said roller.

2. In a device of the kind described, an 65 inking roller having a reservoir therein

opening on the periphery of said roller and adapted to receive a supply of ink, a cover fitting over said reservoir at said peripheral opening, and having an edge spaced from the coöperating opposed edge of the roller to 70 form said peripheral outlet therebetween, and means for controlling the discharge of ink to the periphery of said roller.

3. In a device of the kind described, an inking roller having an ink-receiving reservoir therein opening on the periphery of said roller and adapted to receive a supply of ink, a cover for said reservoir detachably secured to the roller and fitting over said reservoir at said peripheral opening, and means between said cover and opening for adjustably controlling the discharge of ink to the periphery of said roller.

4. In a device of the kind described, an inking roller having an ink-receiving reservoir therein leading to the periphery thereof, a cover for said reservoir and fitting over the peripheral outlet therefrom, and resilient means for adjustably controlling the discharge of ink to the periphery of the roller.

5. An inking roller having an ink-receiving reservoir therein leading to the periphery thereof, a cover detachably secured to said reservoir over its peripheral outlet, and a resilient plate between said cover and roller for adjustably controlling the discharge of ink to the periphery of the roller.

6. An inking roller having an ink-receiving reservoir therein, said roller having a segmental periphery, a segmental cover detachably secured to said roller to form a cylinder therewith, there being an ink-discharge opening leading from said reservoir to the periphery, and means for adjustably controlling the extent of said opening.

7. An ink roller having an ink-receiving reservoir therein, said inking roller having a segmental periphery, a segmental cover for said reservoir and detachably secured to said roller to form a cylinder therewith, there being an ink-discharge opening leading from said reservoir to the segmental periphery, and resilient means for adjustably controlling the extent of said opening.

8. An inking roller having a partly cylindrical inking surface, and having an ink-receiving reservoir therein, a cover for said reservoir detachably secured to said roller, and coöperating therewith to form a substantially cylindrical inking surface, there being an ink-discharge passage between said reservoir and inking surface, a resilient spring plate between said reservoir and cover, and means for adjusting the size of said ink-discharge passage and controlling the amount of ink discharged to the periphery.

9. An inking roller having a partly cylindrical inking surface, and having an ink-receiving reservoir therein, a cover for said

reservoir detachably secured to said roller, and coöperating therewith to form a substantially cylindrical inking surface, there being an ink-discharge passage between said 5 reservoir and inking surface, a resilient spring plate between said reservoir and cover, and means bearing on said plate and adapted to move it for adjusting the size of 10 said ink-discharge passage and controlling the amount of ink discharged to the periphery.

10. An inking roller comprising a cylinder cut away across a chord thereof, and having an ink reservoir opening on said flat 15 surface, a segmental cover over said reservoir and coöperating with said roller to form a substantially cylindrical inking surface, a spring plate between said cover and opening, and means for adjusting the ink 20 passage between the plate and said reservoir so that the amount of ink discharged to the periphery of the roller may be adjustably controlled.

11. In a device of the kind described, an 25 inking roller having an ink-receiving reservoir therein leading to the periphery thereof, a cover for said reservoir detachably se-

cured near one end to the roller, locking means at the other end for preventing relative movement between said members, and 30 resilient means for adjustably controlling the discharge of ink to the periphery of the roller.

12. In a device of the kind described, an inking roller having an ink-receiving reservoir therein leading to the periphery thereof, 35 a cover for said reservoir, a locking bar on one of said members, a lug on the other of said members adapted to seat in said bar to prevent relative movement therebetween, 40 latch means at the other end of said cover for detachably latching it to said roller and preventing relative movement therebetween, and resilient means for adjustably controlling the discharge of ink to the periphery of 45 the roller.

In testimony whereof, I have hereunto signed my name in the presence of two subscribing witnesses.
